UNITED STATES PATENT OFFICE.

JOHN D. PUGH, OF MOUNT WASHINGTON, BALTIMORE, MARYLAND.

LOCOMOTIVE.

Application filed September 11, 1916, Serial No. 119,570. Renewed September 26, 1923.

To all whom it may concern:

Be it known that I, JOHN D. PUGH, a citizen of the United States, residing at Mount Washington, Baltimore, in the county of Baltimore, State of Maryland, have invented certain new and useful Improvements in Locomotives, of which the following is a specification.

The present invention relates to improvements in locomotives and has for its particular object to utilize the power which is ordinarily wasted in steam locomotives and to obtain additional power without increasing the amount of fuel consumed, or to increase 15 the power that is obtainable per horse power hour from a certain amount of fuel.

It is well known that steam at substantially atmospheric pressure when exhausted into a condenser at, for example, 28 inch vacuum, contains practically as much 20 available heat energy as it has between the usual boiler pressures exhausting into the atmosphere; and therefore in, for example, a standard steam locomotive, this energy is 25 entirely lost. By "compounding" a portion of this waste is utilized but in order to recover all of it cylinders of such bulk and other special apparatus are required as to 30 make this practically impossible on steam locomotives.

According to the present invention the power which is thus lost in an ordinary steam locomotive is utilized to actuate a turbo-electric generator connected with motors which will supplement the power of the steam locomotive. That is, by the present invention the exhaust steam from a steam locomotive is employed to operate an electric locomotive so that a maximum amount of 40 the power generated by a certain fuel consumption can be utilized.

The accompanying drawing illustrates, more or less diagrammatically and conventionally, in elevation, one embodiment of the 45 invention.

Referring to the drawing, A represents a standard steam locomotive having a tender B provided as usual with storage means for fuel and a tank or reservoir for water to 50 be supplied to the boiler of the locomotive.

In front of the locomotive A, according to the embodiment of the invention illustrated, is coupled an electric locomotive including an electric generator C and motors D. As 55 shown, the motors are supported on the trucks of the electric locomotive and con-

nected with the axles by gearing arranged within suitable castings E. Similar motors may, if desired, be provided on one or more of the cars of the train. The generator C 60 is adapted to be driven by steam turbine G, the inlet to which is connected through a conduit H with the exhaust outlet of the steam locomotive A. As shown, the turbine G and generator are connected by a train 65 of gears but any other suitable connection between these parts may be employed.

The exhaust from the turbine G is conducted through a conduit K to a condenser L. It will be preferable to employ water 70 as the condensing fluid, although air or other medium may be used, and in the embodiment of the invention this is drawn from the storage tank or reservoir on the tender B of the steam locomotive by a pump 75 M and discharged into the condenser L through a pipe N. The condensed steam and water will be collected in a common chamber or hot well L' at the bottom of the condenser and from this well feed water for 80 the boiler of the steam locomotive may be withdrawn through a conduit l connected with the injector pump a.

To avoid the necessity for a very large storage receptacle for condensing water, it is proposed to provide the apparatus with a cooling tower O into which heated water from the chamber L' will be forced by a pump P and in which tower the water will be acted upon by an air blast created in any 90 suitable manner, as by the motion of the train or by a blower O'. The water cooled in the tower O is returned to the storage tank or reservoir in the tender B of the steam locomotive through a suitable conduit o. 95

As the exhaust steam from the locomotive A is utilized to drive the electric generator a special blower R is provided for creating a force draft in the steam locomotive, said blower being connected with the forward 100 end of the boiler casing through a conduit r.

The necessary auxiliary apparatus, rheostats, etc. of the electric locomotive may be arranged within a compartment S and suitable re-generators or storage batteries within a compartment T. The controlling apparatus for both the electric and steam locomotives may be arranged either within the compartment U of the electric locomotive 110 or the cab of the steam locomotive.

When the apparatus is descending grades

the energy of the weight of the train may be utilized to actuate the motors as generators, the energy thus obtained being transmitted to suitable storage batteries or the electric energy converted into heat which can be utilized for any suitable purpose, as for instance generating steam to be used in driving the turbine G. Power for the motors, the storage batteries and means for changing electric energy into heat may be obtained from an outside source through a suitable collector D', which is connected to the storage batteries, motors and heating element W by suitable wiring which is diagrammatically illustrated in dotted lines. The generator C may also be connected to the storage batteries by suitable wiring illustrated only diagrammatically.

The turbine G is preferably of the so-called low pressure or mixed flow condensing steam type and therefore it will be possible if desired when starting the train to deliver some high pressure steam direct from the boiler of the steam locomotive to the turbine, this steam supply being cut off when the steam locomotive delivers sufficient exhaust to the turbine to properly actuate it.

Means is provided for converting the energy developed by the locomotive and train in descending a grade into heat, which heat may be used in generating steam to drive the turbine, or for other purposes. When it is desired to utilize this heat in generating steam, a construction similar to that illustrated in the drawings may be resorted to. In this construction a boiler Y is supported upon the electric locomotive, which boiler has a connection Z with the feed water pipe and a connection X with the pipe H through which the exhaust steam is conducted to the turbine G. An electrical unit W connected to the wiring leading to the motors D and the collector D' is located within the boiler and is adapted to heat the water therein to create steam to supply the turbo-electric generator.

From the foregoing description and the drawing it will be seen that according to the present invention a considerable portion of the power of a steam locomotive which has heretofore been wasted is utilized. A saturated steam locomotive will consume about 26 pounds of steam per horse power hour and a superheated locomotive about 21 pounds per horse power hour. A low pressure steam turbine such as is hereinbefore referred to may consume approximately 30 pounds of steam per horse power hour. Therefore the power developed by such an arrangement of parts as is hereinbefore described and illustrated in the drawing, assuming the aforesaid steam consumption will be $\frac{30}{26} = 86\frac{2}{3}\%$ or $\frac{30}{21} = 70\frac{1}{3}\%$ of the power developed by the steam locomotive

without any increase in the fuel consumption.

In the drawing the several parts are necessarily illustrated more or less conventionally and diagrammatically and it will be evident that the invention is not limited in any way to the particular arrangement of parts illustrated. There can of course be considerable variation in the form and relative arrangement of the several parts without departing from the spirit of the invention.

Having thus described the invention, what is claimed and desired to be secured by Letters Patent is:

1. The combination with a steam locomotive, of an independently operable electric locomotive detachably connected thereto, said electric locomotive having motors connected to its driving wheels, a generator adapted to be connected to said motors, a collector for obtaining current for said motors from an external source, and a turbine for driving said generator, adapted to be operated by the exhaust steam from the steam locomotive.

2. The combination with a steam locomotive, of a separately operable electric locomotive adapted to be coupled to the steam locomotive and having driving motors connected to the wheels thereof, and means for supplying current for energizing said motors, said means including storage batteries, a collector for obtaining current from an external source, and a generator, said generator being connected to a turbine adapted to be driven by exhaust steam from the engine.

3. The combination with a steam locomotive, of an electric locomotive comprising a generator and motors, a turbine for driving the generator, means for conducting steam exhausted from the steam locomotive to the turbine to actuate the latter, means for condensing the steam exhausted by the turbine, means for conducting heated water from said condenser to the boiler of the steam locomotive, a cooling tower, a pump for conveying water from the condenser to said tower, and means for delivering a blast of air into said cooling tower to pass over the water therein.

4. The combination with a steam locomotive, of an electric generator, motors adapted to be actuated from the generator and adapted to serve as generators when the locomotive is descending a grade, a turbine for actuating the generator adapted to be driven by steam exhausted from the locomotive, and means for converting the energy generated by the motors acting as generators into heat.

5. The combination with a steam locomotive, of an electric generator, motors adapted to be actuated from the generator to supplement the power of the steam locomotive.

5. A turbine for actuating the generator adapted to be driven by steam exhausted from the locomotive, and means for receiving electric energy from an outside source and conducting the same to the motors.

6. The combination with a steam locomotive, of means for utilizing the energy of the steam exhausted thereby, which means includes a steam turbine, a condenser, a cooling chamber for the condensing water, and a fan for causing a current of air to flow through said chamber in contact with the water.

7. The combination with a steam locomotive, of a turbine adapted to be driven by the exhaust steam from the locomotive, an electric generator adapted to be driven from the turbine, motors adapted to be driven by current from the generators, storage batteries, and means for furnishing current to the motors from either the storage batteries or from an outside source.

8. The combination with a steam locomotive, of a separately operable electric locomotive having mounted thereon a turbine adapted to be driven by the exhaust steam from the steam locomotive, an electric generator adapted to be driven from the turbine,

means for collecting current from an outside source, motors adapted to be driven by current from the generator or by current taken from an outside source and which may also serve as generators when the locomotive is descending a grade, and a storage battery for storing the energy thus generated by the motors.

9. The combination with a steam locomotive, of a separately operable electric locomotive adapted to be coupled thereto, said electric locomotive carrying driving motors, an electric generator, a steam turbine, and a blower, and detachable connections between the locomotives whereby exhaust steam from the steam locomotive may be conducted to the turbine and the gaseous current generated by the blower conducted to the steam locomotive, for the purpose set forth.

10. An electric locomotive having drive motors, storage batteries, a device for collecting current from an outside source, a generator adapted to be connected to the motors or storage batteries, and means adapted to be driven by the exhaust steam from a steam locomotive for driving the generator.

In testimony whereof I affix my signature.
JOHN D. PUGH.
